Primary Examiner — Marie D. Fast Horse*(74) Attorney, Agent, or Firm* — WHDA, LLP(57) **CLAIM**

The ornamental design for a docking station, as shown and described.

DESCRIPTION

FIG. 1 is a front perspective view of a docking station showing our new design;

FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is an enlarged partial perspective view thereof, taken along lines 9-9 in FIG. 1.

The broken line seen in FIG. 9 bounding the right and top edges of the enlarged partial figure depict the extent of the enlarged view only and forms no part of the claim. All other broken lines in the drawings depict portions of the docking station that form no part of the claimed design.
